ARTIFICIAL LEG

William T. Carnes, Kansas City, Mo., assignor to
 Carnes Artificial Limb Company, Kansas City,
 Mo., a corporation of Missouri

Original application April 14, 1930, Serial No.
 444,067. Divided and this application November
 3, 1933, Serial No. 696,554

5 Claims. (Cl. 3—2)

This invention relates to artificial limbs. One of the objects of the invention is to produce an artificial limb and foot for amputations above the knee, which will enable the wearer to walk safely and so freely and naturally as to avoid attracting the attention of the casual observer, and to sit down upon a chair or arise therefrom readily and without any noticeable difficulty.

With this general object in view, the invention consists in certain novel and useful features of construction and organization of parts as hereinafter described and claimed; and in order that it may be fully understood, reference is to be had to the accompanying drawings, in which:—

15 Figure 1 is a front perspective view of a man wearing an artificial limb for an amputation above the knee, the view also disclosing a simple and efficient harness forming a part of the invention, for the control of the leg movements in walking and when the wearer seats himself upon or arises from a chair.

Figure 2 is a perspective view to disclose the back part of the harness.

25 Figure 3 is a side view and indicates in dotted lines the position of the artificial limb when the wearer is standing, and as he is starting a forward step with the artificial limb, and also discloses the said limb in a position it may occupy 30 when the wearer is sitting upon a chair.

Figure 4 is an enlarged central vertical section of the artificial limb at and contiguous to the knee joint thereof.

35 Figure 5 is a rear view of the same, with the back wall partly broken away and the back strap omitted, to more clearly disclose certain elements of the internal mechanism.

Figure 6 is a top plan view of the lower leg member and the toggle, the front and back straps being shown in section.

40 Referring now to the drawings, it will be noted that the lower leg portion 1 is hollow at its upper end and that the sides of such end project upwardly and engage pivotally with a cross pin 2, 45 extending transversely through the lower end of the upper leg portion or socket 3 adapted to receive the stump, not shown, of the leg, the lower end of the upper leg portion depending into the upper end of the lower leg portion 1 and being 50 rounded so that it may assume a position at right-angles to the last-named portion as indicated by dotted lines in Figures 3 and 4. Mounted in the lower leg portion 1 in a plane below and rearward of the pivot pin 2, is a pivot pin 4 parallel to pivot pin 2, and mounted on said pivot, and pref-

erably rigid therewith is a toggle, comprising members 5 and 6, the upper end of the latter being pivoted in the side walls of a channel 7 in the rear side of the upper leg portion. The lower member is of channel form and receives the lower end of member 6, and when the members are aligned and the leg is straight, the channel member prevents the toggle breaking rearwardly. When the wearer is seated the toggle is collapsed and the lower member projects forwardly and the upper member downwardly and forwardly. There is a sound-deadening cushion 8 carried by the lower member to prevent a clicking sound being produced as the expansion of the toggles occurs through the straightening of 15 the leg. The lower member has a forward offset 9 carrying a pin 10 engaged by the front strap of a harness, and also has a rear offset 11 coincident with the pivot 4, under which is looped a rear strap of the harness, the lower end of 20 said strap being secured to a pin 12 of said member.

The harness for controlling the knee joint action is constructed as follows: 13 is a front strap which extends around the front side of the 25 rounded knee portion diagonally downward and rearward into the leg portion 1 where it is attached at its lower end to the front cross pin of the toggle. An opposite or rear strap 14 extends along the rear side of the upper leg portion and 30 into the upper end of the lower leg portion where it is attached to the rear cross pin of the toggle. The strap 13 within the lower leg portion passes under a guide roller 15 to minimize frictional contact with the upper leg portion, and a similar 35 roller 16 carried at the upper end of the lower leg portion, serves as a guide for the rear strap 14. The front strap 13, at a point on the upper part of the thigh, runs under one or more guide rolls or keepers 17 for a reason which is herein- 40 after explained, and at a point approximately in the plane of the waist line is attached to a shoulder loop strap 18 which extends over the shoulder in line with the artificial limb, the other end of said strap being attached to the upper 45 end of the strap 14, which also extends through a keeper 17a at the back of the upper leg. A second loop 19, extends over the other shoulder and is attached at its lower ends to the straps 13 and 14 at the junction of the latter with the loop 50 strap 18. A pair of straps 20 and 21 are respectively attached at their lower ends to the front and back straps at the junction therewith of the loops 18 and 19. Strap 20 extends diagonally upward and under the left arm and is attached 55

at its upper end to the back portion of the loop 18 near the upper end thereof. Strap 21 extends diagonally upward and forward and also passes under the left arm and then extends upwardly and forward of the left shoulder and is attached to the front portion of the loop 18 near the top thereof.

Referring further to Sheets 1 and 2 of the drawings, it will be noted that when the artificial leg is straight and the trunk is upright, the straps 13 and 14 fit against the thigh and the body, and are under substantially uniform tension. Now as the wearer starts to step forward with the artificial leg by bringing the thigh upward and forward, he leans forward slightly from the hip. This action results in a relaxation of the front strap and the application of increased tension on the back strap and as a result, the leg bends at the knee in a very natural manner and the foot is lifted, as indicated in the dotted lines *b* of Figure 3. He then swings the leg to position *a*, and straightens the thigh as his body leans back slightly, thus taking up the slack in the front strap and relaxing the back strap. This action pulls the lower or shank portion of the leg in alinement with the thigh portion, and holds it so until the foot is upon the ground and as long as the tension remains on the front strap. Assuming the wearer steps forward with the other foot, he maintains the artificial leg in straight or rigid position until the body is again in a forwardly leaning position and the weight is on both feet, but with the artificial leg still straightened and in line with the inclination of the body. As the weight is transferred wholly to the right leg, and the body is inclined from the hip still further forward, the front strap is relaxed and the rear strap is tensioned. As this occurs the thigh is lifted, the lower portion of the leg is lifted rearwardly, and the leg can be swung forward with sufficient clearance to avoid ordinary ground obstructions, or ascend a stairway. The loop 19 cooperates with the loop 18 in maintaining the front and rear straps in proper relation to the leg, and the under arm straps 20 and 21 prevents the former from slipping sideways, and prevents slippage of the straps 18 and 19 back and forth on the shoulders, and in this connection, it will be noted by reference to Figure 1, that the guide 17 is desirable to hold the front strap closely adjacent the body at the junction of the trunk and thigh, as otherwise when the thigh is raised in taking a step or when the wearer occupies a sitting position as indicated by dotted lines *C*, Figure 3, the front strap would tend to run direct from the point of the knee to the shoulder and hence bulge the wearer's clothing forwardly in a very unsightly manner.

When the wearer is seated the lower portion of the limb may extend at substantially right angles to the thigh portion, and at such time the greatest take up or pulling action is performed by the back strap, and there is a corresponding relaxation of the front strap. In Figure 4, the thigh appears in dotted lines in a substantially horizontal position and through the pull of the back strap, the toggle is swung to substantially the position shown in dotted lines and said toggle incidentally helps take up the slack in the front strap. As the wearer arises to his feet and the thigh approaches a vertically alined position with his body, a pull is applied on the front strap to swing the toggle back to its normal position and the back strap is correspondingly slackened. In other words, it will be seen that

the back strap performs a pulling operation when the wearer is seating himself and that when he is rising from a seated posture, the front strap performs the pulling function. When the leg is straight, the lower end of bar 6 bears against the channel member 6 and thus guards against the leg breaking rearwardly or forwardly at the knee, that is to say, it guards against the lower portion of the leg from swinging forward beyond a position of alinement with the thigh, and also prevents doubling up of the leg until an upward pull is applied on the back strap or pressure is otherwise applied to the break-joint portion of the mechanism. When the leg is bent at the knee substantially at right angles, as indicated by the dotted lines in Figure 4, the break-joint brace is in collapsed condition, the members 5 and 6 thereof extending convergingly forward, and as the leg straightens the angle between the said parts widens until eventually the upper and lower leg members attain an alined position, the member 6 engaging and being arrested by the cushion 8 as such positions of the leg members are attained.

From the above description it will be noted that this application forms a division of my application Serial No. 444,067, filed April 14, 1930, and it will be evident that I have produced an artificial leg embodying the features of advantage set forth as desirable, and while I have described the preferred embodiment it is to be understood that I reserve the right to all changes within the spirit of the invention and without the ambit of the prior art.

I claim:—

1. The combination of an upper leg member and a lower leg member pivoted together, and a toggle pivotally suspended from the upper leg member within the lower leg member, the lower member of said toggle having an upper extension bearing rearwardly against the upper toggle member when the leg is straightened and withdrawn from said upper toggle member when the leg is bent.

2. The combination of an upper leg member and a lower leg member pivoted together, a toggle pivotally suspended from the upper leg member within the lower leg member, the lower member of said toggle having an upper extension bearing rearwardly against the upper toggle member when the leg is straightened and withdrawn from said upper toggle member when the leg is bent, a front strap extending along the front side of the upper leg member and into the lower leg member and attached to the lower toggle member; said strap extending diagonally downward and rearward within the lower leg member when the leg is straight, and being engaged with and bent by the extension of said lower toggle member when the leg is bent to approximately a right angle, and means for exerting an upward pull along the front side of the upper leg member to restraighten the leg.

3. The combination of an upper leg member and a lower leg member pivoted together, a toggle pivotally suspended from the upper leg member within the lower leg member, the lower member of said toggle having an upper extension bearing rearwardly against the upper toggle member when the leg is straightened and withdrawn from said upper toggle member when the leg is bent, a rear strap extending along the rear side of the upper leg member and within the lower leg member and having a looped engagement with the lower end of the lower toggle member and a fixed engagement at its extremity with said toggle.

member at an intermediate point thereof, and means for exerting an upward pull along the rear side of the upper leg member for bringing the leg from a straight to a bent condition.

5 4. The combination of an upper leg member and a lower leg member hinged together, a toggle pivotally suspended from the upper member back of the hinge point of the leg members, the lower member of the toggle having front and rear offset portions at its lower end and an extension at its upper end overlapping the lower portion of and adapted to apply rearward pressure against the upper toggle member above the joint between the toggle members, when the leg 10 is straightened, and a shoulder strap loop having its front end extending along the front side of the upper leg member and down into the lower leg member and attached to the front offset of the lower toggle member, and having its rear 15 end extending along the rear side of the upper leg member and into the lower leg member and looped forwardly under the rear offset of and attached at its end to the lower toggle member at 20 an intermediate point thereof, the extension of said lower toggle member being adapted to engage and bend the front end of the strap loop 25

when the two leg members stand approximately at right angles to each other.

5 5. The combination of an upper leg member and a lower leg member hinged together, a toggle pivotally suspended from the upper member back of the hinge point of the leg members, the lower member of the toggle having front and rear offset portions at its lower end and an extension at its upper end overlapping the lower portion of and adapted to apply rearward pressure against the upper toggle member above the joint between the toggle members, when the leg is straightened, and a shoulder strap loop having its front end extending along the front side of the upper leg member and into the lower leg member and attached to the front offset of the lower toggle member, and having its rear end extending along the rear side of the upper leg member and into the lower leg member and looped forwardly under the rear offset of and attached at 20 its end to the lower toggle member at an intermediate point thereof, the extension of said lower toggle member being adapted to engage and bend the front end of the strap loop when the two leg members stand approximately at right angles 25 to each other.

WILLIAM T. CARNES.
